UNITED STATES PATENT OFFICE.

WILLIAM MENGE, JR., OF DOLGEVILLE, NEW YORK, ASSIGNOR TO DOLGEVILLE FELT SHOE COMPANY, OF DOLGEVILLE, NEW YORK, A CORPORATION OF NEW YORK.

DESIGN FOR A SHOE.

48,190.

Specification for Design.

Patented Nov. 23, 1915.

Application filed August 17, 1915. Serial No. 46,219. Term of patent 3½ years.

To all whom it may concern:

Be it known that I, WILLIAM MENGE, Jr., a citizen of the United States, residing at Dolgeville, in the county of Herkimer and State of New York, have invented a new, original, and ornamental Design for Shoes, of which the following is a specification, reference being had to the accompanying drawing, forming part thereof.

The figure of the drawing is a perspective of a shoe, made according to the original ornamental design, which I have invented. The design involves more particularly, the forming of what is termed the "tongue" in the upper of a shoe, in the form of a shield, of a material of a different color from that

of the vamp, with a scalloped border surrounding it. This, and the ornamental border around the opening of the shoe define very effectively the shield, and produces an attractive effect.

The outlines of the shield are of the conventional heraldic form, and in the center thereof an ornament is set, as shown.

I claim as my invention:

The original ornamental design for a shoe, as shown in the drawing.

WM. MENGE, JR.
